US00D937223S

(12) **United States Design Patent** (10) **Patent No.:** **US D937,223 S**
(45) **Date of Patent:** **** Nov. 30, 2021**

(54) **TERMINAL BLOCK**

(71) Applicant: **OMRON Corporation**, Kyoto (JP)

(72) Inventors: **Tadahiko Ogawa**, Moriyama (JP); **Aiki Kora**, Kyoto (JP)

(73) Assignee: **OMRON Corporation**, Kyoto (JP)

(**) Term: **15 Years**

(21) Appl. No.: **29/761,721**

(22) Filed: **Dec. 11, 2020**

Related U.S. Application Data

(62) Division of application No. 29/690,268, filed on May 7, 2019, now Pat. No. Des. 923,586.

(30) **Foreign Application Priority Data**

(57) **CLAIM**

The ornamental design for a terminal block, as shown and described.

DESCRIPTION

FIG. 1 is a front, top, and right side perspective view of a terminal block showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the terminal block that form no part of the claimed design.

1 Claim, 7 Drawing Sheets
